UNITED STATES PATENT OFFICE

SAMUEL SAMUELSON, OF CLEVELAND, OHIO, ASSIGNOR TO THE CHAIN PRODUCTS COMPANY, OF CLEVELAND, OHIO, A CORPORATION OF OHIO

WIRE CHAIN

Application filed March 9, 1931. Serial No. 521,159.

This invention relates to wire chain of the general form shown in the prior patents to Brown 955,129, April 19, 1910, and Edeburn 1,211,421, January 9, 1917.

5 The objects of the invention are to improve the form and arrangement of the wire to more effectively prevent unlocking or escape of the interlocked free ends of the wire in the finished links and to so bend and lay 10 the wire in the bent loop as to distribute its bearing areas symmetrically to the central plane, whereby the chain lies flat with stability on a flat surface and tracks properly over pulleys without liability to twist or turn. 15 Further objects of the invention are in part obvious and in part will appear more in detail hereinafter.

In the drawings, Fig. 1 is a plan view of a formed chain link blank ready for bending; 20 Fig. 2 is a plan view of the completed link; Fig. 3 is an edge view thereof; Fig. 4 is a perspective view of two consecutive inter-looped links of the finished chain; Fig. 5 is a sectional plan view on the line 5—5, Fig. 25 3; Fig. 6 is a sectional elevation on the line 6—6, Fig. 3; Fig. 7 is a section on the line 7—7, Fig. 3; Fig. 8 is a similar section illustrating a prior construction; Fig. 9 is an end view from the left in Fig. 3; Fig. 10 is 30 a perspective view, on a larger scale, illustrating the formed end of the wire; and Fig. 11 illustrates the action of the wire ends when the chain is under strain.

As in the prior patents referred to, the 35 links of the present chain are each formed from a strip of wire, usually, although not necessarily, of more or less ribbon form, the two free end portions 1 of the wire being bent laterally in the plane of the flat ribbon and then back upon the intermediate portion 2 so that parts 3 of the end portions 1 lie side by side and superposed upon the intermediate portion 2. The terminals of the overlapping portions 3 are also bent laterally in 40 the plane of the wire in more or less zig-zag form so that the terminal 4 of each end portion lies upon or overlaps the other end portion. Blanks so formed are successively produced and are added one by one to the chain 45 being formed by threading a flat blank of the

form shown in Fig. 1 through the superposed twin eyes 5 of the previously formed and attached chain link and then bending the flat blank about a transverse axis at its middle so as to form the rounded loop generally indicated at 6. This bending operation of course occurs not only at the center of the intermediate portion 2 but also where the parts 3 of the end portions lie in side by side relation. The result of the bending operation is, therefore, to more or less interlock the terminal portions 4 in two different planes.

Speaking of the illustration, Fig. 1, for convenience the plane of the paper of the drawings may be called the flatwise plane, because the ribbon metal of the blank may be projected flatwise upon it, while a plane perpendicular to the paper and extending longitudinally of the blank may be called the edgewise plane, because the flat ribbon of the blank may be projected edgewise upon it. Looking at Fig. 1 and considering symmetry of the blank about the central edgewise plane, it will be observed that the two 70 terminal portions have been crossed, as it were, with reference to the edgewise plane. In other words, each end portion 1 intersects the edgewise plane, the major part of the portion 1 lying on one side of said plane and its 75 terminal portion on the other. When the blank is bent to form the loop 6 another crossing of the end portions 1 occurs. In other words, they become crossed in the edgewise direction, or with reference to the flatwise 80 plane, as shown in Fig. 3. This is the same double crossing of the terminal portions that to some extent is accomplished in the afore- 85 said Edeburn patent, although in said patent the crossing in the flatwise direction, seen in 90 Fig. 3 of the present drawings, is not complete, but the terminals are merely brought into edgewise side by side relation.

In these chains, with the terminal portions of the free ends interlocked, when the chain 95 is put under longitudinal strain there is a tendency for the terminal portions to escape from each other by becoming uncrossed in both flatwise and edgewise directions. This object I overcome in very large measure in 100

the present construction by preforming the terminals of the free end portions so as to increase the dimension thereof in the edgewise plane. The preforming may be accomplished in any suitable manner, such as by making it an incident to the shearing operation, which is carried on in a way to distort the metal in the edgewise direction, or by a special swaging or compressing action. The effect is 10 more or less conventionally illustrated in Fig. 10, which shows the metal of the flat ribbon more or less compressed from edge to edge so as to produce a terminal which is thickened in the edgewise direction, giving it an increased dimension at its extreme end along a vertical line in Fig. 10, as shown at A.

Of course, these chains are usually made in rather small sizes of wire, the wire being, for example, $\frac{1}{16}$ th of an inch or so in width and 20 $\frac{1}{32}$ nd of an inch in thickness, so that with the tools commonly employed for cutting and forming this wire fine accuracy of workmanship is impractical, but the operation will be carried out in such manner as to appreciably thicken the wire. As a result, when the two terminal portions are crossed edgewise in the completed link, as shown in Fig. 3, the thickened terminal portions 4 along the edgewise plane is greater than the distance between 30 the neighboring portions B of the wire forming the closed twin eyes 5. The consequence is that when the chain is put under longitudinal strain, the two terminal portions of the wire move up and down in Fig. 3 toward the portions B of the wire, which they contact 35 with in the position shown in Fig. 11. In this position, however, the two swaged terminal portions 4 still overlap each other when viewed edgewise, so that they cannot pass each other along the flatwise plane. As a result, 40 the two terminal portions of the wire are more completely and thoroughly interlocked, so that under longitudinal strain the liability is reduced of these free end portions escaping and projecting out edgewise from the rounded loops with the consequent objections to such action.

In addition, difficulty is experienced with these wire chains when used in certain ways, 50 such as for the suspension of sash weights, by reason of the tendency of the chain to twist or tilt when running over a pulley. This action, which is prevented by the present construction, is best illustrated by comparison of Figs. 7 and 8. Fig. 8 is a duplicate of Fig. 6 of the drawings of the Edeburn Patent 1,211,421. In that construction the wire of the rounded loops 6 is so bent that when a stretch of the chain is laid upon a flat 55 surface, as on a table, in the manner shown in Fig. 4 of the drawings hereof, the chain tends to turn or twist about a longitudinal axis to an inclined position, such as shown in Fig. 8 of the drawings hereof. That is because in the finished link the originally diag-

onal intermediate portion 2 of the original blank extends from one side of one eye 5 to the opposite side of the other eye. In other words, it is still diagonal, and where this crossing intermediate portion presents its 70 surface as a part of the bearing surface of the chain as a whole, it is unsymmetrically located at one side of the central edgewise plane. By "bearing surface" of the chain as a whole I mean the surface which is presented to a table when a chain rests upon it as in Fig. 4 or, in other words, the surface which is presented to a pulley when the chain tracks over a pulley.

Such tendency to twist, in the prior chains of this type, I avoid by special form or configuration of those portions of the wire which form the rounded loops, and particularly those portions which are presented at the oppositely disposed bearing surfaces, one on each face of the chain. At each bearing surface are presented side by side the flat surface of the original diagonal crossing part 2 and a like surface of one of the parts 3 of the free end portions 1, as shown in Figs. 6, 7 and 9. This is accomplished, in effect, by so bending, turning or forming the wire that the two parts are offset from each other in the edgewise plane, the crossing part 2 lying in the recesses thereby produced at the sides of 95 parts 2.

With this arrangement, the chain as a whole has its two bearing surfaces spread out or disposed symmetrically at the two sides of the central edgewise plane so that it tracks 100 squarely on pulleys without tendency to twist or turn.

What I claim is:

1. A chain link, comprising a section of wire bent to form superposed twin eyes at one end and a rounded loop at the other end, the terminal portions of the wire extending past each other and lying side by side within said loop and being thickened to prevent their escape past each other. 105

2. A chain link, comprising a section of wire bent to form superposed twin eyes at one end and a round loop at the other end, the rounded loop including terminal portions of the wire extending past each other in side by side relation and being offset in the central edgewise plane to form recesses and also including a diagonal intermediate stretch of the wire extending from one side of one eye to the other side of the other eye and lying in such recesses, whereby the bearing surface of the link as a whole is symmetrically distributed on either side of said plane. 115

In testimony whereof I hereby affix my signature.

SAMUEL SAMUELSON.
